UNITED STATES PATENT OFFICE

154,860

DESIGN FOR A STEERING WHEEL FOR A VEHICLE

Edward Macauley, Grosse Pointe Farms, Mich.,
assignor to Packard Motor Car Company, De-
troit, Mich., a corporation of Michigan

Application August 9, 1947, Serial No. 140,783

Term of patent 14 years

(Cl. D14—30)

To all whom it may concern:

Be it known that I, Edward Macauley, a citizen of the United States, residing at Grosse Pointe Farms, county of Wayne, State of Michigan, have invented a new, original, and ornamental Design for a Steering Wheel for a Vehicle, of which the following is a specification, reference being had to the accompanying drawing, forming a part thereof.

Figure 1 is a plan view of a steering wheel for a vehicle embodying my invention.

Figure 2 is an enlarged sectional view taken substantially on the line 2—2 of Figure 1 looking in the direction of the arrows.

The characteristic features of my design reside

in the portions shown by means of full lines in the drawing.

I claim:

The ornamental design for a steering wheel for a vehicle, substantially as shown and described.

EDWARD MACAULEY.
